UNITED STATES PATENT OFFICE.

HAYDN THIES HARRISON, OF WESTMINSTER, ENGLAND.

ELECTRIC-ARC LAMP.

Application filed February 4, 1913, Serial No. 274,892, and in Great Britain October 14, 1915.

(GRANTED UNDER THE PROVISIONS OF THE ACT OF MARCH 3, 1821, 41 STAT. L., 1313.)

Applications for patents have been filed in Great Britain on October 14, 1915, and January 11, 1916, in France on January 8, 1917, and in Russia January 17, 1917.

5 This invention relates to that class of electric arc lamp which embodies an electric motor or other rotary device for rotating the carbons, and in which the temperature of the carbons can be kept down by causing a suitable cooling medium, such as a spirit flame, 10 to play about or come in contact with the carbons.

The present invention relates to improved means for feeding the carbons at the required rate, to improved means for causing the striking of the arc to be effected automatically on the lamp circuit being closed, and to the general construction, arrangement, and operation of the parts of the 20 lamp.

In order that the invention may be readily understood reference will be made to the accompanying illustrative drawings in which—

25 Fig. 1 is an elevation showing the general arrangement of a lamp constructed according to the invention.

Fig. 2 is a longitudinal section on the line $x-x$ of Fig. 1.

30 Fig. 3 is a cross section on the line $y-y$ of Fig. 1.

Figs. 4 and 5 show respectively in longitudinal section and in cross section and to a larger scale than Fig. 1, a modified arrangement for feeding the carbons at the desired rate.

35 Fig. 6 shows partly in end elevation and partly in cross section and Fig. 7 in side elevation other arrangements for feeding the carbons.

Fig. 8 is a diagrammatic perspective view showing the arc striking mechanism used in the lamp.

40 Referring to Figs. 1, 2 and 3, A and B are respectively the positive and negative carbons mounted in heads 1, 1^a , (hereinafter called carbon heads) which are supported in stationary parts C of the lamp and are respectively rotated by worm gearing 2, 2^a and 45 3, 3^a operated from a driving wheel 4 rotated by an electric motor 5. The driving wheel 4 is secured on a vertical shaft 6 carrying the worm 2^a of the worm gearing 2— 2^a and is provided at a suitable position

55 with a bevel wheel 7 engaging a bevel wheel 8 fixed to one end of a horizontal shaft 9 that is provided at its other end with a bevel wheel 10. This wheel engages a bevel wheel 11 fixed on a rotatable shaft 12 connected by a flexible coupling 13 to a shaft 14 on to which is fixed the worm 3^a of the worm gearing 3— 3^a .

60 The carbons A and B are each mounted in a metal tube or cartridge 15 from one end of which the forward end of the carbon projects.

To ensure good electric contact with the source of electric supply through the metal tube or cartridge 15, the carbon is forced between metal contact jaws 16. These jaws 70 are formed as a cone clutch (Fig. 2) which is forced at one end against a cone shaped seat 16^a in the carbon head by the cone shaped forward end or head 15^a of the corresponding tube or cartridge 15 and thereby 75 caused to close around and upon the carbon. Each tube or cartridge 15 (hereinafter called a tube) is held in position in the corresponding carbon head in such a way that it can be readily disconnected therefrom when 80 it is desired to insert a new carbon and to be afterwards readily replaced and held in position endways, the projecting end of the new carbon being passed through the carbon head so as to eject the remaining portion 85 of the previous carbon. In the arrangement shown for this purpose, in the Figs. 1, 2 and 3, each tube has fixed to it a collar 15^b that fits the rear end of the carbon head 1 or 1^a and is provided with a circular flange 90 or head 15^c against which normally bears in an endways direction the forked end 17^a of a lever 17. This lever is pivoted at 17^b to a fixed part of the lamp and is held in the operative position by a spring controlled handle 18^c that is jointed at 17^d to an arm 17^c on a lever 17 and is connected by a pin 18^a to one end of a coiled spring 19 the other end of which is connected to a fixed pin 19^a.

100 The arrangement is such that the lever 17 will be held with an elastic pressure in its operative position when the pin 18^a bears against it above the pivot 17^b and it will be moved away from the collar or head 15^c and held in a lowered and inoperative position, to remove endways pressure on the tube 15 and allow the tube to be removed when the handle 18^c and spring 19 are moved 105

downward so as to cause the pin 18^a to bear against a curved seat 18^d on the lever.

Means are provided whereby the tube 15 can be prevented from rotating with the corresponding carbon head when the carbon is to be fed forward, and released, so as to allow it to rotate with the carbon head, when feeding of the carbon is not required. For this purpose, in the example shown in Figs. 1, 2 and 3, the flange or head 15^e is formed with teeth 15^a with which can be engaged a spring controlled detent 15^e that is pivoted at 15^f and can be disengaged from the flange or head by a hand operated lever 15^g when it is desired to release the tube 15 and allow it to be rotated by the carbon head 1 or 1^a, as the case may be.

Each tube 15 is screw threaded internally to engage with a screw threaded carriage or traveller 20 (hereinafter called a traveller), adapted to force the corresponding carbon A forward when the tube 15 is held stationary, the traveller being then rotated relatively to the tube by the carbon which receives its rotary motion from the rotating head through the cone clutch 16. For this purpose, the rear end of the carbon is shaped to fit into a correspondingly shaped hole in the traveller 20, after the manner of a plug and socket joint, so that the carbon and traveller can rotate together. When the tube 15 is held stationary the clutch members 15^a and 16 slip. It will readily be seen that when the travellers 20 in the two tubes 15 are rotated and the tubes 15 are held stationary, the carbons will be fed forward but when the tubes are allowed to rotate with the carbon heads, 1, 1^a, there will be no feeding forward of the carbons.

In the simplest form of the lamp, when it is not desired to regulate the rate of burning of the carbons beyond such regulation as is obtained by suitably winding the electric motor 5, each tube 15 is provided internally with a fine screw thread 15^b (Figs. 1, 2, and 3) of exactly the pitch necessary to produce the required rate of feed of the carbon.

Or, if the required screw thread 15^b would be too fine to be conveniently cut, the traveller 20 can be connected to the rotating carbon through a suitable speed reducing gear whereby the speed of rotation of the traveller can be reduced relatively to the speed of rotation of the carbon. A convenient form of reducing gear of this kind is shown in Figures 4 and 5 wherein there is keyed or otherwise connected to one end of the carbon, marked B, a circular block 21 to which is secured a spindle 22, carrying a pinion 23. A sleeve 24 is mounted on the block 21 and is provided with a feather 25 engaging in a slot 26 in the tube 15. The sleeve 24 is provided with an internally toothed wheel 27. The traveller 20, which

is screw threaded externally and engages the screw thread 15^a of the tube 15, is provided with a spindle 28 on which is mounted a loose pinion 29 that gears with the pinion 23 and with the wheel 27. The parts are held together by a head 22^a on the spindle 22 screwed into the block 21. The rotation of the carbon B rotates the circular block 21 and the pinion 23, which rotates the pinion 29, and as the wheel 27 is fixed, the pinion 29 and its spindle 28 are carried round the wheel 27, thereby effecting the rotation of the traveller 20 at a slower rate than that of the carbon. As the traveller is engaged with the said thread 15^a of the tube 15, the traveller and consequently the carbon and associated parts are fed forward. By suitably choosing the number of teeth on the respective wheels 23, 27 and 29, any desired reduction in the speed of rotation of the traveller 20 relatively to that of the carbon B can be obtained.

Where, owing to variation in the rate of consumption of different batches of carbons, or for any other reason, it may be desired to vary the rate of feed of the carbon, when the lamp is burning, the form of feed mechanism shown in Figure 6 may be employed. In this case the tube 15 is so arranged as normally to rotate with the carbon head 1 or 1^a and carbon A or B, so that no feeding of the carbon then takes place, and means are provided whereby rotation of the tube can be arrested when desired to enable the traveller therein to be fed forward by screwing itself endways in the tube. Various means may be provided for arresting the rotary motion of the tube under the action of a moving part of the lamp for the purpose set forth. In the example shown for this purpose in Fig. 6, a ratchet wheel 30 is used that is fixed on the tube 15 and cooperates with a stop device, shown as a pawl 31 carried on a pivoted bell crank lever 32, 33, one arm namely 33, of which is loaded as by making it heavier than the arm 32, or by providing it with a counterweight 33^a or equivalent, the other arm 32 being provided with a roller 34 or the like that bears against a cam or eccentric 35 or equivalent lever operating device. The cam 35 is rotated either directly or indirectly, by a suitable rotating member of the lamp, for instance the corresponding rotating carbon holder 1 or 1^a. When the pawl 31, under the control of the cam 35 or equivalent device and the action of the weighted arm 33 of the lever 32—33 is caused to engage the ratchet wheel 30, the rotation of this wheel and tube 15 is stopped, and the carbon is then fed forward by the rotation of the traveller 20 in the tube during each period of rest of the tube. The duration of each period of rest of the tube 15 can be adjusted externally to the tube by altering the relative positions of the pawl 31 130

and the roller 34, or other equivalent means may be employed.

The pawl clutch member 32-33, or equivalent may be attached to a rod that can be depressed or raised by hand to throw the arresting device out of or into operation when desired and thus allow of the carbon feed being effected by hand.

Fig. 7 shows another feeding arrangement wherein the tube 15 used in the other arrangement, is dispensed with and the rotary carbon A is moved endways by a traveller 20 that is engaged by a screw threaded rod 36, which runs parallel to the carbon 15 marked A, and is rotated by any convenient means from a moving part of the lamp but is prevented from moving endways. In the example shown, the second rod 36 is rotated in an intermittent manner, by one or more pins 37, one being shown, carried by the worm wheel 2 of the worm gearing 2, 2^a used for rotating the corresponding carbon head 1, the pin 37 being arranged to engage a star wheel 38 fixed on the screw threaded rod 36. It will thus be seen that each time the screw threaded rod is partly rotated, the traveller 20 will be moved forward carrying the carbon A with it. The screw threaded rod 36 is supported at its end by fixed parts 36^a, 36^b of the lamp and it may be provided with a hand wheel 36^c by which it can be rotated by hand, when desired.

In order to cause the striking of the arc to be effected in an automatic manner on closing the switch controlling the lamp circuit, and also at other times during the working of the lamp, there is employed a movable contact piece 39, (Figs. 1 and 8) consisting for example of a finger of carbon, metal or other suitable conducting material. This contact piece is secured to an arm 39^a fixed on a spindle 40 which is mounted in bearings 40^a and oscillated about a horizontal axis by a rod 41 connected to a crank pin 40^b on the spindle 40. The rod 41 is provided with an extension 41^a by means of which it can be raised by a rotary cam 42 fixed on the horizontal shaft 9. The rod, at its lower end, is connected to the armature 43 of an electro-magnet 44, or solenoid, in series with the lamp circuit. On the lamp circuit being closed and the carbon heads 1, 1^a set in rotation by the motor 5 through the shafts 6 and 9, the cam 42 will, during its rotation, permit the collar 41^a and rod 41 to fall and turn the spindle 40 and arm 39^a in a direction to cause the contact piece 39 to touch the opposing tips of the carbons A, B, if it is not already doing so, and on the cam afterwards acting to raise the extension 41^a and rod 41, the contact piece 39 will be withdrawn to form an electric arc between the carbons. The contact piece is then further withdrawn from the region of the arc by the operation of the armature 43 of the electro-

magnet 44 or equivalent, which is now excited owing to the lamp circuit being completed through the arc and the winding of the electro-magnet, the armature retaining the contact piece in the retracted safe position as long as the current is flowing (see Fig. 8). The cam 42 can then no longer act upon the rod 41, owing to the upward movement of the rod 41 having removed its operative part 41^a out of engagement with the cam 42. On the current ceasing to flow across the carbons, the armature 43 will fall away from the electro-magnet 44, under the action of gravity, or its equivalent, and thereby, through the downward movement of the rod 41 with extension 41^a, enable the cam 42 to again come into operation to again cause the contact piece 39 to move into and out of contact with the carbon tips and so again cause the arc to be struck if the circuit switch be still closed.

If desired, more than one movable contact piece mounted and operated as hereinbefore described with reference to the contact piece 39 may be used to prevent any possible failure to strike the arc when required.

The carbon heads 1, 1^a are preferably arranged at an angle to one another as shown.

What I claim is:—

1. An electric arc lamp of the class described comprising opposite rotary carbon holders, means for preventing endwise movement thereof, a motor having connections for rotating said carbon holders in unison, rotary feeding mechanism associated with each holder and actuated therefrom to feed a carbon therethrough, and means for disconnecting either feeding mechanism. 100

2. In an electric arc lamp of the class described, a rotary carbon holder, means for preventing endways movement thereof, a motor connected to rotate said holder, means for automatically feeding a carbon endwise through the holder while being rotated thereby, a toothed member upon said holder, and a cooperating engaging member to retain the holder against rotation to effect a feed of the carbon. 110

3. In an electric arc lamp of the class described, a rotary carbon holder provided with a friction clutch adapted to engage and rotate a carbon while permitting an endwise feed therethrough, a motor, means for rotating said carbon holder therefrom, an internally screw threaded tube normally held in frictional driving connection with said rotary holder, means for retaining said tube against movement when desired, a traveller for moving the carbon endwise, and feeding means for said traveller engaging the thread of the tube and thereby actuated from the rotary holder. 120

4. In an electric arc lamp of the class described, a rotary carbon holder constructed 130

- to clamp and rotate a carbon while permitting endwise feed therethrough, a tube disposed co-axial with said carbon and holder and frictionally engaged with the latter, a 5 traveller located within the tube and actuated by the rotary motion thereof, and a control lever arranged to retain the tube in such frictional engagement.
5. In an electric arc lamp of the type 10 herein referred to, a rotary carbon holder adapted to clamp and rotate a carbon extending therethrough but so as to admit of the carbon being moved endways, an internally screw threaded tube arranged co-axial 15 with said carbon holder and associated carbon, and in releasable engagement with said carbon holder so as to rotate therewith, means whereby said tube can be held stationary, a traveller located within the tube 20 and in operative engagement with the screw threaded portion of said tube, a rotary body adapted to exert endways pressure on the rear end of the carbon and speed reducing mechanism disposed within the tube and 25 comprising an annular gear and pinions between said rotary body and traveller.
6. In an electric arc lamp of the kind in 30 which each carbon is rotated about its longitudinal axis by an electric motor, a movable contact device under the control of the motor whereby it is adapted automatically to move into a position to bridge the tips of the carbons and afterwards to be moved away therefrom by the motor to strike an 35 arc between them and means for holding the contact piece out of the control of the motor when an arc is formed between the carbons.
7. In an electric arc lamp of the kind in 40 which each carbon of a pair thereof is rotated about its longitudinal axis, a movable conducting contact device adapted to bridge the tips of the carbons, means adapted, when the lamp is in action, to cause the contact 45 device to move against and from the carbons to strike an arc between them and electro-magnetic means the circuit of which is arranged to be closed through the arc and adapted, when an arc is formed between the carbons, to hold the contact device in an 50 inoperative position.
8. In an electric arc lamp of the kind in 55 which each carbon of a pair thereof is rotated about its longitudinal axis, a movable conducting contact device adapted to bridge

the tips of the carbons, oscillating means adapted to move the contact device towards and from the carbons to strike an arc between them, a cam device operated from a moving part of the lamp, and adapted to bring about the oscillation of the oscillating means, and electro-magnetic means the circuit of which is arranged to be closed through the arc and adapted, when an arc is formed between the carbons, to hold the contact device in an inoperative position. 60

9. In an electric arc lamp of the kind in which each carbon of a pair thereof is rotated about its longitudinal axis, a movable conducting contact device adapted to 65 bridge the tips of the carbons, a lever arm carrying said contact device, a rotary body carrying said arm, a rod connected to said body and adapted to oscillate the same and attached arm and contact device, said rod being adapted to move endwise automatically, in one direction, a cam operated from a moving part of said lamp and adapted to move said rod in the opposite direction and electro-magnetic means the circuit of which is arranged to be closed through the arc and adapted, when an arc is formed between the carbons, to hold the contact device in an inoperative position. 70

10. In an electric arc lamp of the kind in which each carbon of a pair thereof is rotated about its longitudinal axis, a movable conducting contact device adapted to bridge the tips of the carbons, a lever arm carrying said contact device, a horizontal 75 spindle mounted to turn about a horizontal axis and to which said arm is fixed, a vertical rod connected to said spindle and adapted to oscillate it and the attached arm and contact device, said rod normally having a 80 tendency to fall and move said contact device against the tips of the carbons, a rotary cam adapted to be continuously operated from a moving part of the lamp when the lamp is in action and to move the rod 85 in a direction to withdraw the contact device from the carbons and an electro-magnet having its winding arranged to be in the circuit of the arc when struck and having an armature adapted when attracted to raise 90 the said rod and hold the contact device in its inoperative position. 100

Signed at London, England, this eleventh day of December, 1918.

HAYDN THIES HARRISON.
